INVENTOR:
WILLIAM P. McHUGH.

BY *Edward E. Longan*

ATTORNEY.

UNITED STATES PATENT OFFICE.

WILLIAM P. McHUGH, OF ST. LOUIS, MISSOURI.

DESIGN FOR A COMBINED AMPLIFYING AND TELEVISION DEVICE.

Application filed March 25, 1929. Serial No. 30,617. Term of patent 14 years.

To all whom it may concern:

Be it known that I, WILLIAM P. McHUGH, a citizen of the United States of America, residing in St. Louis and State of Missouri, have invented a new, original, and ornamental Design for Combined Amplifying and Television Devices, of which the following is a specification, reference being had to the accompanying drawing, forming a part thereof, in which—

Fig. 1 is a front view of the article showing my new design; and

Fig. 2 is a perspective view of the same

with the doors opened showing the interior thereof. The dominant feature of my design is the artistic representation in miniature of a theatrical stage, including a screen on which is painted a scene, substantially as shown in Fig. 2 of the drawing.

I claim:

The ornamental design for a combined amplifying and television device, as shown and described.

In testimony whereof I have signed my name to this specification.

WILLIAM P. McHUGH.
